United States Patent Office.

JULIUS L. D. SULLIVAN, OF SOMERVILLE, MASSACHUSETTS.

Design No. 3,489, dated May 11, 1869.

DESIGN FOR A FIREMAN'S BADGE.

The Schedule referred to in these Letters Patent and making part of the same.

To all whom it may concern:

Be it known that I, JULIUS L. D. SULLIVAN, of Somerville, in the county of Middlesex, in the State of Massachusetts, have originated a new Design for a Fireman's Badge, of which the following is a full, clear, and exact description, reference being had to the accompanying photograph, making part of this specification.

The invention relates particularly to the configuration and ornamentation of badges to be worn by members of steam fire-engine organizations, the design being intended to embrace, upon its face, representations of an engine, and the apparatus pertaining thereto.

The accompanying photograph shows a badge embodying the design.

Upon the centre of the badge is a representation of the engine in elevation, and around this, and forming the frame of the picture or badge, are various implements or parts of the apparatus adjunctive to the engine, or connected with the occupation of firemen.

On the opposite sides are seen the ladders, sur-

mounted by two spanners, a plate for the name or location of the engine, and a shield, with monogrammatic initials.

On the inner edges of each ladder, is a suction-hose pipe, above whose top projects a fire-hook, and whose lower end projects through a bend in a leading-hose, two sections of which hose form the bottom of the badge or frame, the coupled ends bending around into an auxiliary frame, which may be used for engraving the name of the fireman, or for any other purpose to which its form and location adapt it.

The badge is thus made to embrace all or nearly all of the apparatus peculiar to the occupation of a fireman.

I claim the design for a fireman's badge, substantially as shown and described.

JULIUS L. D. SULLIVAN.
